UNITED STATES PATENT OFFICE.

JAMES G. HALLAS, OF KENOSHA, WISCONSIN.

MACHINE-CHUCK.

1,242,182.

Specification of Letters Patent.

Patented Oct. 9, 1917.

Application filed June 15, 1916. Serial No. 103,712.

To all whom it may concern:

Be it known that I, JAMES G. HALLAS, a citizen of the United States, and resident of Kenosha, in the county of Kenosha and State 5 of Wisconsin, have invented new and useful Improvements in Machine-Chucks, of which the following is a description, reference being had to the accompanying drawings, which are a part of this specification.

10 The invention relates to work holders or vises more particularly for use on shapers, planers and milling machines.

The usual form of work holder for machines of this character consists of fixed 15 and movable jaw members with means for operating the movable jaw, the fixed jaw member also forming the supporting base for the work. The difficulty with devices of this kind is that the work is not held firmly 20 against the base of the holder and the essential object of this invention is to obviate this difficulty by providing an attachment which may be used in connection with the usual form of work holder and which automatically 25 exerts a downward pressure upon the work to hold it against the supporting base when the work is secured within the holder.

The invention further consists in the several features hereinafter set forth and more 30 particularly defined by claims at the conclusion hereof.

In the drawings:

Figure 1 is a view of the device embodying the invention, parts being broken away and 35 parts being shown in section;

Fig. 2 is a section taken on the line 2—2 of Fig. 1;

Fig. 3 is a section taken on the line 3—3 of Fig. 1;

40 Fig. 4 is a detail vertical sectional view of a modified form of the device.

The device with which the attachment is combined comprises a fixed jaw member 10 provided with a jaw 11 and supporting base 45 12, a movable jaw member 13 having a depending portion 14 slidably mounted in a guideway 15 in the base 12, and means for moving the jaw 13 with respect to the jaw 11 and its base 12. This means consists of a 50 screw shaft 16 having threaded engagement with the portion 14 of the member 13 and journaled in a lug 17 on the base, said shaft 16 having a square end 16' for receiving a wrench to turn it.

The attachment for exerting a downward 55 pressure upon the work comprises a block 18 slidably mounted upon the base 12 and provided with tapered pins 19 adapted to be disposed in apertures 20 or 21 in the members 11 and 13. These pins 19 serve to keep the 60 block 18 in proper position with respect to the base. It sometimes happens that the work is wider at one end than at the other and to provide for properly gripping the 65 work I have formed the block with a vertically extending guide 22 having a convex surface 23 disposed centrally of the block and adapted to contact with the face of either jaw member so that the block may be inclined with respect to the jaws to accommodate for irregular pieces of work.

The block 18 is provided with a transversely extending circular bore 24 formed near the top and the outer side 25 of the block has a transversely extending inclined 75 slot 26 leading from the outer side 25 of the block 18 to the bore 24. This bore 24 and the connecting slot 26 form an opening for receiving a gripping member 27. This member 27 comprises a curved portion 28 which is adapted to be seated in the bore 24 and a downwardly inclined portion 29 integral with the portion 28 and adapted to project through the slot 26 and beyond the outer side 25 of the block, the sides of said portion 80 28 converging to a transversely extending rounded work engaging edge 30. The seating of the portion 28 within the bore 24 allows of limited pivotal movement of the member 27 with respect to the block, the side 85 31 of the slot 26 serving as a stop for this purpose. The member 27 is normally held up against the side 31 by a spring 32 which is secured to it at one end by a screw 33 and washer 34 and its other end is seated in a 90 recess 35 in the block 18. It will be noted that the shape of the member 27 is such that its work engaging edge 30 is disposed below the axis of the portion 28 and at a distance 95 from the center bore 24 and portion 28. The 100 other end of the gripping member is provided with a threaded bore 36 for receiving

a screw 37 carrying a washer 38, said washers 34 and 38 serving to secure said member against endwise movement within the block.

As previously pointed out the attachment 5 is adapted to be placed adjacent either the fixed or the movable jaw member, or as shown in Fig. 1 an attachment may be disposed against the gripping faces of both jaw members.

10 The arrangement of the gripping member and block and the disposition of the work engaging edge with respect to the pivotal support of the gripping member within the block is such that when lateral pressure 15 is applied to the work engaging edge it will move downward, thus exerting a downward force upon the work upon the table and at the same time exerting a lateral force to coöperate with the other jaw member or 20 with the gripping member of the attachment disposed against the other jaw member. In brief when the attachment is positioned 25 against the gripping face of the fixed jaw member and the work is disposed between said attachment and the movable jaw member, and the movable jaw member is moved inwardly, the work will be gripped 30 between the movable jaw and the gripping member, and, as the vise is tightened, the gripping member exerts both a lateral force 35 against the work and a downward force causing it to be firmly pressed against the supporting base of the vise. It will be noted that this gripping member acts automatically to perform the functions above 40 pointed out when brought into engagement with the work. If attachments are used for both jaw members, each will operate as above pointed out, and the work will be held 45 against lateral movement between the gripping members and will also be held tightly against the supporting base of the vise through the downward force automatically exerted by the gripping members against the work when they are brought into engagement therewith, as shown in Fig. 1 where the work 39 rests on spacing blocks 40.

50 In Fig. 4 I have shown a slightly modified form of device in which the blocks of the attachment are made integral with the jaws of the vise and a similar gripping member is secured and connected thereto as the gripping member of the construction first described and the action and function 55 of the gripping member is the same in this instance as that previously described.

The invention thus exemplifies a vise in which one or both of the gripping faces of the vise are provided with movable gripping members which exert both a lateral and downward force against the work and do this automatically on their being brought

into engagement with the work through the lateral movement of the vise jaws with respect to each other.

65

What I claim as my invention is:

1. The combination, with a vise comprising a fixed jaw member having a supporting base, a movable jaw member and means for operating said movable jaw member, of a 70 block removably connected with one of said jaw members and slideable along the base and having a transversely extending bore near the front side thereof and a slot extending from the front side to said bore, a 75 member mounted within said bore for limited pivotal movement and having a gripping portion extending outwardly through the slot and provided with a work engaging edge disposed in a plane below the plane 80 of the pivotal axis of said member to automatically exert a lateral and downward pressure against the work on the tightening up of the jaw member.

2. The combination, with a vise comprising 85 a fixed jaw member having a supporting base, a movable jaw member and means for operating said movable jaw member, of a block operatively connected with one of 90 said jaw members, a gripping member pivotally secured in said block and having a work engaging edge projecting outwardly from the same and disposed below its pivotal axis to automatically exert a downward pressure 95 against the work on the tightening up of the jaw members, and means for normally maintaining said gripping member in its upper position.

3. The combination, with a vise comprising 100 a fixed jaw member having a supporting base, a movable jaw member and means for operating said movable jaw member, of a block operatively connected with one of 105 said jaw members, a gripping member pivotally secured in said block and having a work engaging edge projecting outwardly from the same and below its pivotal axis to automatically exert a downward pressure 110 upon the work on the tightening up of the jaw members, and a spring secured to said block and gripping member to maintain said gripping member in its normal upper position.

4. An auxiliary attachment for a machine vise comprising a block having squared ends, a gripping member pivotally secured 115 in said block and having a work engaging edge projecting outwardly from the same below its pivotal axis, and means for normally maintaining said gripping member in 120 its upper position.

In testimony whereof, I affix my signature.

JAMES G. HALLAS.
